CLAIM

The ornamental design for a watch dial, as shown and described.

DESCRIPTION

FIG. 1 is a perspective view of a watch dial showing my new design;
FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The dashed broken lines in the drawings are for the purpose of illustrating unclaimed portions of the watch dial and form no part of the claimed design, and the dash-dot-dash broken lines illustrate the boundary of the claimed design.
